UNITED STATES PATENT OFFICE

NORMAN H. RICKER, OF HOUSTON, TEXAS, ASSIGNOR TO HUGHES TOOL COMPANY, OF
HOUSTON, TEXAS, A CORPORATION OF TEXAS

GAS OPERATED SWAB

Application filed April 10, 1930. Serial No. 443,013.

My invention relates to swabs for use in water and oil wells, and pertains particularly to means whereby the gaseous fluid in the well may be employed to raise the liquid to the surface.

My device is designed for use where there is gas pressure in the well but in insufficient quantities to cause the liquid to flow therefrom.

10 It is an object of the invention to provide an apparatus wherein this gaseous fluid pressure can be used to operate a swab for raising liquid to the surface.

I desire to entrap the gas ordinarily leaking from the well, and to collect the same below the swab until sufficient pressure is obtained to elevate the swab and its load of liquid.

15 In the drawings Fig. 1 is a central vertical section through the upper end of a device embodying my invention.

Fig. 2 is a similar section through the lower end of the device.

20 In the use of my device, the well is equipped with a casing 1, the lower end which may be perforated at 2 to allow the entrance of gas and liquid. The upper end of the casing is connected to a casing head 3 having a lateral outlet 4 for the fluid. The lower end 25 of the head has an internal flange 5, the upper side of which provides a shoulder 6 to support the discharge head 7 of the inner pipe 8. The upper end of the casing head is closed by an elongated bull plug or cap 9.

30 The inner pipe 8 is connected with the head 7 at its upper end. This head fills the lower part of the casing head and rests upon the flange 6 of said casing head. At a point below the outlet 4 the head 7 is decreased in 35 external diameter and extended upwardly in the casing head and bull plug. The reduced upper end is slotted at 10 to allow an outlet for fluid.

40 A buffer for the swab is provided at the upper end of the inner pipe. An extension 11 on the said pipe is connected with a housing 12 in which is seated a cushion 13 of rubber or similar material. Said cushion has a central opening 15 to allow expansion of 45 the rubber, and the upper end of the cap 9

on the casing has a second cushion 14 to act with the buffer 13 in extreme cases where the buffer 13 is insufficient to stop the swab where it is forced upwardly beyond its normal stroke and in case of destruction of the 55 said buffer 13.

The lower end of the eduction tube is connected by a coupling 16 to an inlet tube 17, the lower end of which is flared outwardly at 18 to provide a bell opening to collect the 60 gas entering the casing.

Within the eduction tube is shown a swab plunger or barrier 19 similar to that shown in a co-pending application of myself jointly with H. W. Fletcher, Serial No. 313,742, 65 filed October 20, 1928. This plunger is cylindrical on its outer surface to fit the tube. Its inner passage is tapered downwardly and a valve 20 closes the passage at the lower end. Said valve has a downwardly extending 70 guide stem 21, which slides in a support 22 on the lower end of the plunger.

The valve is open when the plunger is falling to the lower end of the eduction tube, and is adapted to be closed at the lower end 75 of its stroke by a pin or post 23 formed centrally of the plate or disc 24 clamped between the ends of the tube at the coupling 16. The disc 24 is perforated to allow the 80 passage of fluid therethrough.

85 In the operation of my device, the plunger will seat upon the plate 24, and the pin engaging the valve stem will force it to closed position. The gas in the well will gather in the tube 17 below the plunger and will accumulate until sufficient pressure is obtained to raise the plunger with its load of liquid. The liquid will eventually be discharged 90 through the openings 10 and outlet pipe 4 to storage. As the load of liquid above the 95 plunger is relieved, the plunger will be accelerated in speed and will be forced past the openings 10 by the gas pressure. The valve 20 will be forced open by the fluid in the upper end of the tube, and the plunger will 100 then drop back to the bottom of the eduction tube.

The submergence of the lower end of the eduction tube will be regulated so that the proper load of liquid will rise in the educ- 105

tion tube when the fluid pressure in the tube is relieved by the discharge of the load at each upward stroke of the plunger. The plunger will therefore sink through the liquid above the plate 24 and will seat thereon to close the valve 20 as previously noted. The gas will then gather below the plunger until sufficient pressure is obtained to again lift the plunger and its load of liquid.

10 In the drawings, the plunger is shown as just starting upwardly with its load of liquid. The gas escaping past the lower end of the accumulator 18 in the casing is allowed a vent through the opening 25 in the 15 casing below the casing head.

15 The advantage of my invention lies in its simplicity and its automatic action. The liquid may be raised to the surface with my apparatus where otherwise the gas pressure 20 could not be utilized for the purpose.

25 What I claim as new is:

25 1. A device of the character described, including a well casing, a casing head thereon having a lateral discharge opening, an eduction tube in said casing, a plunger in said tube, an accumulator pipe at the lower end of said tube to receive gas from the well, a perforated plate between said tube and accumulator pipe, a valve in said plunger, and 30 means on said plate to close said valve.

35 2. A device of the character described, including a well casing, a casing head thereon having a lateral discharge opening, an eduction tube in said casing, means to support said tube in said casing head, a bell-shaped gas accumulator at the lower end of said tube, a plunger in said tube above said accumulator movable from the lower end to the upper 40 end of said tube and a normally open valve in said plunger adapted to be closed by gas pressure.

45 3. A device of the character described, including a well casing, a casing head thereon having a lateral discharge opening, an eduction tube in said casing, means to support said tube in said casing head, a bell-shaped gas accumulator at the lower end of said tube, a normally open valve in said plunger adapted to be closed by gas pressure, a 50 plunger in said tube, and means at the upper end of said accumulator to support the said plunger at the lower end of its stroke.

55 4. A well swabbing device, including a casing, a casing head thereon, an eduction tube, a swab plunger in said tube adapted to move the full length of said tube, a normally open valve in said plunger adapted to be closed by gas pressure and means to accumulate gas from the well below said swab to raise the 60 same with its load of liquid to the surface.

65 5. A well swabbing device, including a casing, a casing head thereon, an eduction tube, a swab plunger in said tube adapted to move the full length of said tube, a normally open valve in said plunger adapted to be closed

by gas pressure, a support for said plunger adjacent the lower end of said tube, and means below said support to receive and accumulate gas from the well below said plunger.

70 6. A well casing, a casing head thereon, an eduction tube supported in said casing head, a swab plunger working in said tube, a normally open valve in said plunger adapted to be closed by gas pressure, a support for said plunger adjacent the lower end of said tube, and a pipe below said plate flared outwardly at its lower end to receive and accumulate gas from said well below said plunger.

75 7. The method of automatically raising liquid from wells containing a body of liquid and a seepage of gas thereinto, which consists in interposing a vertically movable barrier between the bottom of a column of liquid in the well and a gas-receiving space under 80 said column, and confining an accumulation of gas pressure in said space below said barrier to force upward said barrier for a distance limited only by the top of the well and the amount of gas, and maintaining an open 85 discharge outlet above said space, whereby the gas pressure will automatically force up said liquid column and cause said liquid to flow from the well.

90 8. The method of automatically raising liquid from wells containing a body of liquid and a seepage of gas thereinto, which consists in interposing a vertically movable barrier between the bottom of a column of liquid in the well and a gas-receiving space under 95 said column, and confining an accumulation of gas pressure in said space below said barrier to force upward said barrier for a distance limited only by the top of the well and the amount of gas, and maintaining an open discharge outlet above said space, whereby 100 the gas pressure will automatically force up said liquid column and cause said liquid to flow from the well, and repeating said operations by the automatic downward gravitation 105 of said barrier upon the release of the gas pressure and its reascent after another confinement and accumulation of gas pressure below said barrier, as described.

110 In testimony whereof, I hereunto affix my signature, this the 2nd day of April, A. D. 1930.

NORMAN H. RICKER.
